CLAIM

The ornamental design for a keyboard with fingerprint sensor, as shown and described.

DESCRIPTION

FIG. 1 is a perspective view of a keyboard with fingerprint sensor disclosing my new design;

FIG. 2 is a top plan view;

FIG. 3 is a front view;

FIG. 4 is a left side view;

FIG. 5 is a right side view;

FIG. 6 is a rear view;

FIG. 7 is a bottom view;

FIG. 8 is a perspective view of a modified form of the keyboard and fingerprint sensor;

FIG. 9 is a top view of the design shown in FIG. 8;

FIG. 10 is a front view of the design shown in FIG. 8;

FIG. 11 is a left side view of the design shown in FIG. 8;

FIG. 12 is a right side view of the design shown in FIG. 8;

FIG. 13 is a rear view of the design shown in FIG. 8; and,

FIG. 14 is a bottom view of the design shown in FIG. 8.

The phantom lines appearing in FIGS. 1, 2, 8, and 9 are solely for indicating adjusted positions of groups or sets of keys and this does not form part of the instant invention.
